CLAIM

The ornamental design for an acu-point magnet, as shown and described.

DESCRIPTION

FIG. 1 is a perspective view of the acu-point magnet; FIG. 2 is a front side, a rear, a left side, and a right side view, each view is the same, thereof; FIG. 3 is a top plan view thereof; and, FIG. 4 is a bottom plan view. The broken lines in the drawings depict environmental subject matter of the acu-point magnet only and form no part of the claimed design.
